US0D1017840S

(12) **United States Design Patent** (10) **Patent No.:** **US D1,017,840 S**
(45) **Date of Patent:** **** Mar. 12, 2024**

(54) **WATERPROOF SCREW COVER**

(71) Applicant: **Up Way Systems, Lda.**, Vila Nova de Famalicão (PT)

(72) Inventor: **Pedro Filipe Gomes Carvalho**, Vila Nova de Famalicão (PT)

(73) Assignee: **Up Way Systems, Lda.**, Vila Nova de Famalicão (PT)

(**) Term: **15 Years**

(21) Appl. No.: **35/512,920**

(22) Filed: **Aug. 25, 2021**

(80) **Hague Agreement Data**

Int. Filing Date: **Aug. 25, 2021**

Int. Reg. No.: **DM/217108**

Int. Reg. Date: **Aug. 25, 2021**

Int. Reg. Pub. Date: **Nov. 12, 2021**

(51) **LOC (14) Cl.** **25-99**

(52) **U.S. Cl.**

USPC **D25/199**; D8/499

(58) **Field of Classification Search**

USPC D25/48.1, 48.2, 199; D8/399, 499, 19, D8/14, 16

CPC F16B 37/14; F16B 33/004; F16B 43/001; E04D 5/145; E04D 5/143

See application file for complete search history.

(57) **CLAIM**

The ornamental design for waterproof screw cover, as shown and described.

DESCRIPTION

1. Waterproof screw cover

1.1 : Top side view

1.2: Top perspective view

1.3: Bottom view

1.4 : IN-USE VIEW

The broken lines rendered in 1.4 illustrates the environment of the claimed design and forms no part thereof.

1 Claim, 4 Drawing Sheets

US D1,017,840 S
